UNITED STATES PATENT OFFICE.

MAX MAYER, OF NEW YORK, N. Y.

DESIGN FOR A MOUTHPIECE FOR PIPES.

SPECIFICATION forming part of Design No. 25,772, dated July 14, 1896.

Application filed May 25, 1896. Serial No. 593,061. Term of patent 3½ years.

To all whom it may concern:

Be it known that I, MAX MAYER, a citizen of the United States, residing in the city, county, and State of New York, have invented and produced a new and original Design for Pipe-Mouthpieces, of which the following is a specification.

The leading feature of my design is a pipe-mouthpiece having a shank configured on opposite sides by a V-shaped groove.

A pipe-mouthpiece embodying my design is shown in the accompanying drawings, the said mouthpiece being shown in side view in Figure 1, in plan view in Fig. 2, and in section in Fig. 3, the section of Fig. 3 being taken on the line 3 3 of Fig. 2.

Referring particularly to the drawings, 1 is the body of the pipe-mouthpiece, from which a nipple 2 projects. Adjoining the body at the end thereof, opposite to the nipple 2, is a shank 3, which extends from said body and is grooved on opposite sides with V-shaped grooves 4 and terminates in a nipple 5.

What I claim is—

The design for a pipe-mouthpiece having the essential features described herein and shown in the drawings.

MAX MAYER.
